BOILER

Charles W. Brabbée, Bronxville, N. Y., assignor to
American Radiator Company, New York, N. Y.,
a corporation of New Jersey

Original application February 2, 1931, Serial No.
512,924. Divided and this application July 21,
1933, Serial No. 681,423

11 Claims. (Cl. 110—100)

My invention relates to improvements in heating apparatus, and the same has for its object to provide a boiler for heating purposes which is simple in construction, efficient in operation, and 5 convenient to manufacture.

Further, said invention has for its object to provide a sectional boiler of the magazine type which will burn anthracite or bituminous coal, or coke, or mixtures thereof, as desired.

10 Further, said invention has for its object to provide a boiler in which means are provided whereby the combustion chamber may be connected directly with the chimney or stack to facilitate the starting of the boiler.

15 Further, said invention has for its object to provide a sectional, magazine boiler in which bypass means are provided for short-circuiting the draft at the commencement of the firing operation.

20 Further, said invention has for its object to provide a boiler comprising a plurality of transverse sections each of which embodies a proportionate part of the ashpit, fuel receptacle and combustion chamber, magazine, flue parts and air ducts.

25 Further, said invention has for its object to provide a sectional boiler having a series of flues leading from the fuel receptacle and combustion chamber, and a plurality of collecting flues connecting the said flues with the smoke outlet, and means whereby either one of said collecting flues may be simultaneously placed in communication with the smoke outlet and the other closed to said smoke outlets.

30 Further, said invention has for its object to provide a boiler having a large fuel capacity, and a comparatively small burning area whereby to insure a long operating period without necessity for refueling.

35 Further, said invention has for its object to provide a sectional, magazine boiler in which the fuel magazine, combustion chamber, fuel receptacle and ashpit are arranged substantially to one side of a center line of the boiler, and flue portions to the other side of said line.

40 Other objects will in part be obvious and in part be pointed out hereinafter.

To the attainment of the aforesaid objects and ends my invention consists in the novel features of construction, and in the combination, connection, and arrangement of parts herein-after more fully described and then pointed out in the claims.

45 In the accompanying drawings wherein like numerals of reference indicate like parts—

Figure 1 is a front elevation showing one form of boiler constructed according to and embodying my said invention;

Fig. 2 is a back view;

Fig. 3 is a face view of an intermediate section;

Fig. 4 is an enlarged detail elevation partly in section showing the construction and arrangement of the main and the short-circuiting dampers, and the actuating means therefor, both dampers being shown in closed positions;

Fig. 5 is a top view of the parts shown in elevation at Fig. 6;

Fig. 6 is a view similar to Fig. 5 showing the main damper open, and the short-circuiting damper closed;

Fig. 7 is a top view of the parts shown in elevation at Fig. 8;

Fig. 8 is a view similar to Figs. 4 and 6, showing both main and short-circuiting dampers in open position, and

Fig. 9 is a top view, partly in section of the parts shown in elevation at Fig. 8.

In said drawings 15 designates the boiler as a whole comprising a front section, a back section, and a plurality of corresponding intermediate 25 sections 18. The front is provided at about its central portion with an observation opening 19; below and to the left of said observation opening with two slicing openings 20, 20, and below said slicing openings with an ash pit opening 21. In 30 the upper left hand corner is provided fuel opening 22 communicating with the fuel magazine 23. Adjacent to the upper right hand side of the front section is provided a clean-cut opening 24 and directly below said clean-cut opening 24 is 35 provided a larger clean-cut opening 25, affording access to the flues.

The back section is provided adjacent to its upper left hand corner (as seen from the rear) with a smoke outlet 26, and near the middle adjacent to the base with a cold air inlet 27 communicating with the ash pit.

The boiler proper, comprising the assembled sections 18, is wholly enclosed in a sectional metal jacket 28 provided upon its inner side with insulating lining members 29.

Each intermediate section 18 includes a peripheral water-way 30 and peripheral beads 31 upon each of its opposite surfaces which are adapted to register with corresponding beads of the contiguous sections to form close joints. Each section 18 further includes a magazine portion which extends downwardly from the top of the boiler about the center thereof, and there merges with an enlarged portion forming in part a fuel re- 55

- ceptacle and combustion chamber portion 34. The fuel receptacle 34 extends from one side of the boiler towards the opposite side thereof, and terminates at a point beyond the vertical center 5 of the boiler. The fuel receptacle is provided with a grate 35 consisting of a plurality of bars 35^a each one of which is pivotally mounted at its opposite ends within one of the intermediate sections 18 of the boiler.
10. Each grate bar 35^a has a depending arm 36 adjacent to one of its ends, the alternate of which are connected to two bars 37, 37^a whose forward ends extend through the front section of the boiler and are pivotally connected to shaking levers 39, 39^a, respectively, which have their lower ends pivotally connected to the body of the boiler and their upper ends free and adapted to detachably receive the end of a separate shaking arm, not shown. The space below the grate 35 constitutes 20 the ash receptacle 40.

The portion of each intermediate section 18 between the right hand side thereof and the left-hand side of the fuel receptacle, combustion chamber, and ash pit forms, adjacent to the top 25 of the boiler, a steam dome member 41, and a reversible flue which, at its entrance portion 42 overhangs the fuel receptacle and combustion chamber. The right-hand wall 43 of the fuel receptacle and combustion chamber is formed by 30 a tubular water-way 44 which extends from the base portion of the section, upwardly and thence angularly inwardly towards the lower end of a short tubular member 45 constituting the lower 35 end of the inner wall of the fuel magazine 23 to which it is united by a smaller tubular portion 46 whereby to form between it and the corresponding 40 tubular members 46 of the sections adjacent at each side a series of openings 42 for the hot gases and products of combustion. The flue space is 45 further divided into a descending portion 48 and an ascending portion 48^a by a depending tubular partition portion 49 which extends rearwardly and downwardly towards the lower transverse water way 48^b constituting the base of the ash 50 receptacle, and at its lower end said depending tubular partition portion 49 is connected by short tubular members 50 with the tubular water way 44 and with the vertical right-hand peripheral water way 38 of the section, and similar short tubular members 51 serve to connect the same 55 parts with the tubular partition member 49 about midway of its height.

The descending flue part 48 communicates at 55 its upper end with a longitudinal short-circuiting flue 52 which communicates at one end with the smoke outlet 26, and the ascending flue part 48^a communicates with a similar collecting flue 52^a which communicates at its corresponding end with the smoke outlet 26.

60. 53 denotes a smoke hood which is bolted to the rear of the boiler over the smoke outlet 26 therein. Within said smoke hood 53 are pivotally mounted a large horizontally-swinging damper 54^a which substantially corresponds in outline 65 with the longitudinal collecting flue 52^a, and a smaller horizontally-swinging damper 54 which fits over the rear end of the longitudinal short-circuiting flue 52. The lower end of the damper 54^a is provided with an ear 55 to receive the 70 upper end of a pivot pin 56 secured in the bottom of the smoke-hood 53, and the upper end of said damper is provided with a similar ear 56^a in which is fixed the lower end of a shaft 57, whose upper end extends through an opening in the top 75 of the smoke-hood 53, and has fixed upon its

projecting end an operating arm 58 having an upwardly projecting pin 59 at its free end adapted for engagement with a recess 60 in a reciprocable bar 61 which has its opposite ends slidably mounted in bearings 62, 62 secured to the top of 5 the smoke-hood.

The smaller damper 54 has integrally formed shaft members 63 and 64 at its upper and lower ends which extend respectively through suitable openings in the top and bottom of the smoke-hood 53. The upper or longer shaft member 63 is also provided at its upper projecting end with a fixed arm 65 having an upwardly projecting pin 66 at its free end adapted for engagement with a second recess 67 in the bar 61. 10

15. The bar 61 is provided adjacent the entrance end of each recess 60, 67 with projections 68—68^a which severally serve as cams to cause each of the pins 59, 66 on the arms 58, 65 to be guided into its respective recess in the bar 61, when the 20 latter is reciprocated.

The bar 61 is further provided between the recesses 60, 67 with a slotted portion 68^b to loosely receive a pin 70 fixed at the lower free end of an arm 71 whose other end is secured to the rear end 25 of a shaft 72 extending through the boiler from the front to the back thereof. At the front of the boiler the forward end of the shaft 72 is provided with an operating handle 73 with which is associated an indicating plate 74 secured upon 30 the front of the boiler, to indicate the several positions of the dampers 54^a, 54.

The operation in general of the boiler will be largely obvious from the foregoing description. It is to be noted, however, that when first firing 35 the cold boiler it is desirable that the fuel be ignited rapidly, and that the produced smoke and products of combustion shall find their way most easily and rapidly to the smoke outlet and stack.

To obtain this result the damper control handle 40 73 at the front of the boiler should be moved to the extreme left, thereby partially rotating the shaft 72, and the arm 71, secured to said shaft at the rear of the boiler to the right, as shown at Figs. 8 and 9, and at the same time shifting the 45 bar 61 correspondingly in the same direction. In the course of said movement the bar 61 will cause the projection 59 on the arm 58, operating the damper 54^a, to pass out of the recess 60 in said bar 61, and come into engagement with the 50 inner edge of said bar, and thereby rotate the arm 58 about forty-five degrees (45°), and in so doing cause the damper 54^a to wholly open the outlet of the collecting flue 52^a leading to the outlet 26, as seen at Fig. 8. As the bar 61 moves 55 to the right, as just above described, the projection 68 on said bar will contact with the pin 66 of the arm 65 fixed to the shaft 63 operating the short-circuiting damper 54, and guide said pin 66 into the recess 67 of said bar, and thereby 60 partially rotate said shaft 63 and wholly open the short-circuiting damper 54 controlling the short-circuiting flue 52, thus permitting the smoke and products of combustion to pass simultaneously from the short-circuiting flue 52 directly into 65 the smoke-hood 26, and mingle with the gases and products of combustion entering the smoke-hood from the flue 52^a, and thence pass therewith into the stack. When the fuel is fully ignited and burning properly, the handle 73 is 70 moved to the extreme right, and the shaft 12 correspondingly rotated thereby causing the bar 61 to be moved to the left, as shown at Figs. 4 and 5, and the associated parts to function to close both the main damper 54^a and the short- 75

circuicting damper 54. By this movement of the bar 61 to the left the pin 66 of the arm 65, controlling the short-circuicting damper 54, will be caused to pass out of its recess 67 in the bar 61, and ride upon the inner surface of said bar, and at the same time the projection 68^a of the bar 61, will contact with the pin 59 of the arm 58 controlling the main damper 54^a, and cause said pin 59 to enter its recess 60 in the bar 61, and cause said arm 58 to be carried to the left, thereby closing said main damper 54^a, and the short-circuicting damper 54, as shown at Figs. 4 and 5, and hold both of said dampers in their closed positions until the bar 61 and its operating parts are again actuated.

When the main damper 54^a and the short-circuicting damper 54 are adjusted to their closed positions, as shown at Figs. 4 and 5, sufficient space will be left between the outlet end of the collecting flue 52^a, and the edges of the damper 54^a to allow for the escape of gases and products of combustion liberated by the fuel in the course of the normal operation of the boiler.

When it is necessary or desirable to open only the main damper 54^a without opening the short circuicting damper 54, as, for example, when refueling the boiler, it merely requires the adjusting of the handle 73 to the vertical or intermediate position whereupon the damper 54^a and the actuating parts therefor will assume the positions shown at Figs. 6 and 7, and permit of substantially all of the gases and products of combustion to pass through the collecting flue 52^a, smoke-hood 53, and into the stack.

This application is a division of my earlier application Serial No. 512,924, filed February 2, 1931, which resulted in Letters Patent No. 1,924,077, dated August 22, 1933.

Having thus described my said invention, what I claim and desire to secure by Letters Patent is:

1. A boiler including a fuel receptacle and combustion chamber, a smoke outlet, a collecting flue and a short-circuicting flue connecting said combustion chamber with said smoke outlet, a valve for said collecting flue, and a valve for said short-circuicting flue, a reciprocable bar, means for supporting said bar, cam means on said bar, means carried severally by said dampers coacting with the cam means on said bar, and means for reciprocating said bar whereby to actuate said valves jointly to control the passage of gases and products of combustion through said flues.

2. A boiler including a fuel receptacle and combustion chamber, a smoke outlet, a collecting flue and a short-circuicting flue connecting said combustion chamber with said smoke outlet, a valve controlling the outlet of said collecting flue, and a valve controlling the outlet of said short-circuicting flue, a reciprocable bar, means for sup-

porting said bar, cam means on said bar, means carried severally by said dampers for engagement with the cam means on said bar, and means for reciprocating said bar whereby to actuate said valves jointly to control said flue outlets and the passage of gases and products of combustion through said flues.

3. A boiler including a fuel receptacle and combustion chamber, a smoke-hood, a collecting flue and a short-circuicting flue having separate, adjacent outlets opening into said smoke-hood, said flues connecting said combustion chamber with said smoke-hood; a valve for said collecting flue, and a valve for said short-circuicting flue, a reciprocable bar, means for supporting said bar, cam means on said bar, means carried severally by

said dampers for engagement with the cam means on said bar, and means for reciprocating said bar whereby to actuate said valves jointly to control the passage of gases and products of combustion through said flues. 5

4. A boiler including a fuel receptacle and combustion chamber, a smoke-hood, a collecting flue and a short-circuicting flue having separate outlets opening into said smoke-hood, said flues connecting said combustion chamber with said smoke-hood, a valve mounted in said smoke-hood controlling the outlet of said collecting flue, and a valve also mounted in said smoke-hood controlling the outlet of said short-circuicting flue, a reciprocable bar, means for supporting said bar upon said smoke-hood, cam means on said bar, means carried severally by said dampers for engagement with the cam means on said bar, and means operable from the front of the boiler for reciprocating said bar whereby to actuate said valves to control the passage of gases and products of combustion through said flues. 10 15

5. A boiler including a fuel receptacle and combustion chamber, a smoke-hood, a collecting flue and a short-circuicting flue having separate outlets opening into said smoke-hood, said flues connecting said combustion chamber with said smoke-hood, a valve mounted in said smoke-hood controlling the outlet of said collecting flue, and a valve also mounted in said smoke-hood controlling the outlet of said short-circuicting flue, a reciprocable bar, means for supporting said bar, cam means on said bar, shafts extending severally from said valves through said smoke-hood for engagement with the cam means on said bar, and an operating shaft engaging said bar for reciprocating the same whereby to actuate said valves to control the passage of gases and products of combustion through said flues. 20 25 30 35

6. A boiler including a fuel receptacle and combustion chamber, a smoke-hood, a collecting flue and a short-circuicting flue having separate outlets opening into said smoke-hood, said flues connecting said combustion chamber with said smoke-hood, a valve mounted in said smoke-hood controlling the outlet of said collecting flue, and a valve also mounted in said smoke-hood controlling the outlet of said short-circuicting flue, a reciprocable bar, means for supporting said bar, cam means on said bar, shafts extending severally from said valves through said smoke-hood, arms on the ends of said shafts for engagement with the cam means on said bar, a shaft extending through the boiler and operable from the front thereof, and an arm on the rear end of said shaft engaging said bar for reciprocating the same whereby to actuate said valves to control the passage of gases and products of combustion through said flues. 40 45 50 55

7. A boiler including a fuel receptacle and combustion chamber, a smoke-hood, a collecting flue and a short-circuicting flue having separate outlets opening into said smoke-hood, said flues connecting said combustion chamber with said smoke-hood, a damper mounted in said smoke-hood controlling the outlet of said collecting flue, and a damper also mounted in said smoke-hood controlling the outlet of said short-circuicting flue, a reciprocable bar, means for slidily supporting said bar, cam means and recesses on said bar, shafts extending severally from said dampers through said smoke-hood arms secured to the projecting ends of said shafts for engagement with the cam means and certain of the recesses on said bar, and an operating shaft extending 60 65 70 75 75

- through the boiler and operable from the front thereof, an arm secured to the rear end of said shaft engaging with the remaining recess in said bar for reciprocating the same whereby to actuate said dampers and hold the same to adjusted positions to control the passage of gases and products of combustion through said flues.
8. A boiler comprising an ashpit, a fuel receptacle and combustion chamber, a smoke outlet, flues extending from said fuel receptacle and combustion chamber, a plurality of collecting flues connecting said first-named flues with said smoke outlet, valves adjacent the outlet ends of said collecting flues for severally controlling the passage of gases from said collecting flues to said smoke outlet, a shaft extending through the boiler from the front to the back thereof, means connecting the rear end of said shaft with said valves, and an operating handle secured to the forward end of said shaft.
- 15 9. A boiler comprising an ashpit, a fuel receptacle and combustion chamber, a smoke outlet, flues extending from said fuel receptacle and combustion chamber, a plurality of collecting flues connecting said first-named flues with said smoke outlet, a smoke-hood secured over said smoke outlet, a pair of valves pivotally supported in said smoke-hood for controlling the outlet ends of said collecting flues, arms secured to said valves, a reciprocable member engageable with said arms to actuate said valves, a shaft extending through the boiler from the front to the back thereof; the rear end of said shaft engaging said reciprocable member, and an operating handle secured to the forward end of said shaft for actuating the same.
- 20 10. A boiler comprising an ashpit, a fuel recep-

tacle and combustion chamber, a smoke outlet, flues extending from said fuel receptacle and combustion chamber, a plurality of collecting flues connecting said first-named flues with said smoke outlet, a smoke-hood secured over said smoke outlet, a pair of valves pivotally supported in said smoke-hood for controlling the outlet ends of said collecting flues, shafts on said valves extending vertically through said smoke-hood, arms each fixed at one end to the projecting end 10 of one of said valve shafts, a reciprocable member mounted upon said smoke-hood, means on said reciprocable member engageable with the free ends of said arms whereby to open both of said valves or to open one of said valves and hold the other closed, and an operating shaft extending longitudinally of the boiler and having its rear end operatively associated with said reciprocable member, and a handle secured to the forward end of said shaft.

20 11. In a boiler having a plurality of smoke outlets, a valve for controlling each of said outlets, supporting means for said valves, shafts extending from said valve through said supporting means; each of said shaft having an arm fixed 25 at one end thereto and a pin extending from the other end thereof, a bar slidably mounted upon said supporting means having recesses therein each engageable with one of the pins on said valve shaft arms, a shaft extending longitudinally 30 of the boiler, an arm having one end fixed to said shaft and its other end operatively associated with said bar, and an operating handle at the forward end of said shaft for operating said shaft whereby to cause the arm at its rear end to actuate said bar to open and close said valves.

CHARLES W. BRABBEÉ.
